UNITED STATES PATENT OFFICE

WALTER BORTH, OF CHEMNITZ, GERMANY

MAGNESIUM LAMP FOR PHOTOGRAPHIC PURPOSES

Application filed January 6, 1931, Serial No. 507,006, and in Germany January 18, 1930.

My invention relates to illuminating lamps to be used in taking photographs, and more especially to lamps of the class in which the light is produced by the combustion of a piece of magnesium of like combustible metal, which burns away within a relatively long period of time—one or more seconds—when compared with the momentary and explosion-like combustion of cartridges containing flash light powder—usually finished in about 1/50 second—as used in connection with well-known but materially different classes of illuminating lamps.

Magnesium lamps are preferably used in many cases, especially for taking indoor photographs, because of the relatively small volume of their flame, their low burning speed and the absence of hissing noise, which are factors of safety and comfort: By reason of the comparatively long time of exposure—one second and longer—during which light produced by magnesium lamps is active upon the photographic plate, only a flame of an accordingly small volume is required which yet has the same photochemical effect as the many times more powerful illumination necessarily produced by flash light powder lamps in which the combustion lasts only about 1/50 second.

Persons to be photographed are therefore less likely to be dazzled and irritated by the light produced by magnesium lamps; moreover strips of wire of magnesium, in which form the latter is mostly used in practice, are altogether a more harmless illuminating medium than those cartridges or bags containing flash light powder which are known to occasionally emit sparks and cause considerable danger, e. g. to curious people, children etc. who inadvertently come too near the suddenly rising and relatively large flame of a flash light lamp.

For obtaining an efficient illumination it has been customary heretofore to use lamps in which a plurality of strips of magnesium are simultaneously burnt; however, although those strips are usually rather narrow and cut from thin magnesium foil in order to more easily catch fire and evenly burn away, their simultaneous ignition often causes an-

noyance and disappointment, because of the tendency of the strips to roll up, and the working with magnesium lamps therefore calls in many cases for considerable skill and experience on the part of the operator. It can happen that some of the strips of magnesium will not catch fire at all or do not start and do not finish burning at the same time, so that their illuminating effect is considerably impaired.

The principal object of this invention is to provide a structurally simple and inexpensive magnesium lamp of improved design which can be easily and safely manipulated even by unskilled operators, viz. amateurs in the photographic art.

Another object of the invention is to thus design the magnesium lamp that the volume and intensity of the flame developed gradually increases during the illumination from zero to a maximum, so that the risk of dazzling and irritating persons to be photographed is greatly reduced or eliminated.

Other objects of the invention will become apparent hereinafter.

The nature and scope of my invention are briefly outlined in the appended claims and will be more fully understood from the following specification taken together with the accompanying drawing, in which an illuminating lamp and pieces of magnesium foil, to be used therewith and exhibiting the salient features of this invention, are shown by way of examples.

Fig. 1 is a front elevation of the lamp ready for use, partly shown in section taken on line 1—1 of Fig. 2.

Fig. 2 is a plan, partly shown in section, taken on line 2—2 in Fig. 1.

Figs. 3-6 show a few modifications in the shape of the triangular piece of magnesium foil designed for the purposes of this invention.

Briefly described the improved magnesium lamp consists of a substantially triangular piece of magnesium foil, *a*, of means for keeping said piece of magnesium foil freely suspended in upright position with two of its corners at substantially the same height, while the third corner presents its

lowest point, and of means for igniting said triangular piece of magnesium foil from below.

In the embodiment of my invention shown by way of an example in the drawing the means for keeping the triangular piece of magnesium foil freely suspended in the specified upright position comprises a casing 1, open at the top,—a cover *d* hinged to said casing, so as to be capable of being swung upwardly into an upright position,—a hoop *b*, hinged to said cover *d* at its inner side, so as to be capable of being swung outwardly and away from the cover *d*, when the latter is in its upright position,—and slotted clamps *c* provided at the outer ends of the said hoop *b*, into which the said triangular piece of magnesium foil *a* is inserted with two of its corners.

In the embodiment of the invention shown by way of an example in Figs. 1 and 2 the means for igniting the triangular piece of magnesium foil comprise a burner *e*, pivotally mounted at *h* within the casing 1 and spring actuated means under the control of the operator for moving the burner *e* from an idle position into its working position right underneath the lower corner of the triangular piece of magnesium foil.

The combustible body *a* consists of a cut-out sheet of foil and is tapered towards one end. Preferably it has the form of an isosceles triangle, as shown in Fig. 1. The apex, which hangs downwards, forms the point of ignition. The fastening to a holder *b* is effected at the two corners of the base line. The combustible body holder *b* consists of a hoop open towards the front, which has at the two lateral ends small clamps *c*, in which the combustible body is lightly clamped. The holder hoop is arranged in a casing *l* with the cover *d*. The holder hoop can preferably be rotatably mounted on the casing cover *d* by means of a bushing or tube *m*, in order to enable the lamp to be folded up and carried conveniently in the pocket. The inside of the cover is polished and serves as a reflector.

For igniting the combustible body *a* a movable burner *e* is provided, which is supported by a lever *g*. The lever is rotatable about a vertical axis *h* and is connected to a lever *i*. Between said lever and the vertical wall of the casing a spring *k* is arranged. The burner can be brought into the igniting position shown by a wire release *f* or by an automatic release or by clockwork.

Ignition of the combustible body *a* is effected by the flame of the burner *e* at the lower end and requires, by reason of the small amount to be first heated and melted, only the shortest time, indeed 1 second calculated from the moment of hand operation, whilst with several strips, many times this amount of time is consumed during ignition.

With the present combustible body the ignition occurs therefore so precisely, that it is possible to cause several lamps to be ignited simultaneously by means of a manifold release, which otherwise could hardly be attained in general with magnesium ribbon lamps. After kindling, the burning proceeds from the lower point to the upper base line of the triangle with increasing rapidity. The increase in luminosity as the burning proceeds has the advantage in that the brilliant effect of the glaring light is considerably less unpleasant, so that unsightly closing of the eyes in photographing persons is avoided.

Various changes and modifications may be made in the structural details of illuminating lamps of the improved design described above and also in the specific shape of individual triangular pieces of magnesium foil to be used therewith, without departing from the spirit and the leading ideas of my invention.

In order to modify the sharp contours of the shadows thrown, the source of light must also receive a sufficient expansion. For this purpose the base line of the triangular combustible body can have a greater breadth, whereby it is true, the apex angles would be increased and as a consequence a delay in igniting would follow. In order to prevent this, the sides of the triangle whilst retaining the small apex angle, can be replaced by broken lines or curves, so that shapes similar to that in Fig. 3 are obtained.

The upper base line can also be formed as a curve, in order to obtain approximately equal distance from the point of ignition to the furthest metal parts of the base line and to produce as near as possible a burning of the whole surface up to the end. The plane surface would then be equal to or similar to a quadrant, as, for instance, shown in Fig. 4.

The corners at the base line could also be made blunt or rounded, in order to avoid damage when fixing up the thin foil, so that the triangular or heart-like shapes shown as examples in Figs. 5 and 6 would be obtained.

I am aware that apart from thin sheets or foils of magnesium, used as fuel for illuminating lamps, and of which triangular pieces are used in connection with this invention—a rapidly burning flash light composition is known in the art, which is mixed with a cementing material and is spread out so as to form a foil: I make no claim neither to any specific flash light composition nor to its application in the form of a foil per se.

Nevertheless—although simply magnesium foil is specified above as being the material from which the triangular pieces are made, to be used in connection with my invention, I do not wish to restrict myself to foils of pure magnesium, in as much as foils

made of appropriate alloys of magnesium, burning also at a relatively low rate of speed and producing brilliant light may obviously be used instead and would give substantially the same illuminating effect of gradually increasing power which is one of the main objects of my invention.

What I claim is:

1. In a magnesium lamp for photographic purposes, a casing, a holder in said casing, a sheet of magnesium foil tapered towards its lower end, said sheet being suspended on said holder, a burner, a lever rotatable in a horizontal plane and supporting said burner, an operating lever connected to said supporting lever and adapted to move said burner into igniting position, and a spring between said operating lever and a wall of said casing, said spring being adapted to 20 retract said burner from its igniting position.

2. In a magnesium lamp for photographic purposes, a flat casing, a cover for and rotatably connected to said casing, a hoop open toward the front and rotatably mounted on the inside of said cover, clamps at the two front lateral ends of said hoop, said clamps being adapted to sustain a sheet of magnesium foil, and a movable burner in said 30 casing for igniting said foil.

3. In a magnesium lamp for photographic purposes, a horizontal flat casing, a cover for said casing, said cover being rotatably connected to said casing and adapted to be brought into a vertical position, a hoop open toward the front, said hoop being rotatably mounted on the inside of said casing and adapted to be brought to a horizontal position, clamps positioned at the two front 40 lateral ends of said hoop, said clamps being adapted to sustain a sheet of magnesium tapered towards its lower end, and a movable burner in said casing, said burner being adapted to be moved from an inoperative 45 position to the operative position below the tapered end of said foil.

4. In a magnesium lamp for photographic purposes, a horizontal flat casing, a cover for said casing, said cover being rotatably connected to said casing and adapted to be brought into a vertical position, and said cover having a polished lower surface adapted to serve as a reflector, a hoop open toward the front, said hoop being rotatably mounted on the inside of said casing and adapted to be brought to a horizontal position, clamps at the two front lateral ends of said hoop, said clamps being adapted to sustain a sheet of magnesium tapered towards its lower end, and a movable burner in said casing, said burner being adapted to be moved from an inoperative position to the operative position below the tapered end of said foil.

5. In a magnesium lamp for photographic

purposes, a flat casing, a cover for and rotatably connected to said casing, a hoop open toward the front and rotatably mounted on the inside of said cover, clamps at the two front lateral ends of said hoop, a sheet of 70 magnesium foil tapered towards its lower end, said sheet being held by said clamps, and a lever rotatable in said casing, said lever supporting a burner adapted to be brought under the lower end of said foil.

6. Illuminating lamp for the purpose set forth, comprising in combination a substantially triangular piece of combustible metal foil, burning at a relatively low rate of speed and producing brilliant light, means for 80 keeping said piece of metal foil freely suspended in upright position with two of its corners being at substantially the same height, while its third corner presents the lowest point, and means for igniting said 85 piece of metal foil.

7. Illuminating lamp, having the features set forth in claim 6, in which the means for keeping the said triangular piece of metal foil freely suspended in the specified position comprise—a casing open at the top, a cover hinged to said casing, so as to be capable of being swung upwardly into an upright position, a hoop hinged to said cover at its inner side, so as to be capable of being 90 swung outwardly and away from the cover, and slotted clamps provided at the outer ends of said hoop and being adapted to receive the piece of metal foil, inserted thereinto with two of its corners.

8. Illuminating lamp having the features set forth in claim 6, in which the means for igniting the metal foil comprise a burner, pivotally mounted and being cooperatively associated with spring actuated means under the control of the operator for turning the said burner from an idle position into its working position right underneath the metal foil.

In testimony whereof I have affixed my 110 signature.

WALTER BORTH.
